CHARLES EDWARD ENNIS, OF KANSAS CITY, MISSOURI, ASSIGNOR TO WALLS FROGLESS SWITCH & MANUFACTURING COMPANY, OF KANSAS CITY, MISSOURI, A CORPORATION OF COLORADO.

SWING-RAIL SWITCH-FROG.

1,309,023.

Specification of Letters Patent.

Patented July 8, 1919.

Application filed May 7, 1918. Serial No. 233,001.

To all whom it may concern:

Be it known that I, CHARLES EDWARD ENNIS, a citizen of the United States, and a resident of Kansas City, in the county of 5 Jackson, State of Missouri, have invented a certain new and useful Improvement in Swing-Rail Switch-Frogs, of which the following is a full, clear, and exact description.

My invention is an improvement in swing- 10 rail switch frogs and it relates in particular to a mounting for the movable rail section and the means for swinging the rail section from one position to the other. The principal objects of my invention are to provide 15 a frog which can be renewed by replacing one rail only, in a much shorter time than the present frog in common use can be renewed, and without the need of tearing up the track; to provide novel and simplified 20 means for swinging the movable rail section; to provide a mechanism for moving the parts of a switch which will tend to clean itself of snow, ice or debris and pre- 25 clude the need of attention when heavy snows occur; and withal to provide a device which will be able to withstand the heavy 30 duties placed thereon on account of heavy traffic and which shall be so simple in construction and operation that it may be readily 35 installed and maintained by the ordinary track man.

In the single sheet of drawings accompanying this application and forming a part hereof—

35 Figure 1 is a plan view of a swing-rail switch frog embodying my invention, certain of the parts being broken away to reduce the size of the figure;

Fig. 2 is a perspective view of the same 40 parts on a slightly larger scale;

Fig. 3 is a vertical section taken through the pivot point of the swinging rail section; and

Fig. 4 is a perspective view of the four- 45 armed rocking lever which operates the parts.

Referring to the drawings, in which like characters of reference designate like parts in the several views, 1 indicates a base plate 50 on which the swinging section is mounted and to the ends of which the main and switch track rails A, B, C, and D are secured. These rail ends are held in place by the side plates 2 and spreaders 3, which 55 spreaders serve to give the rails the proper

angle of divergence. Preferably the side plates, rail ends and spreaders are all joined into a unitary structure by horizontal bolts 4 and the side plates are securely bolted to the base plate by bolts 5 so that the rails 60 may not creep with relation to the swinging section and thus interfere with the action of the latter by binding. The swinging rail section E is mounted to oscillate about a pivot 6 at its center. This pivot consists of a bolt 65 which passes through a circular opening in the base plate 1 and which has an enlarged head 7 resting on the upper face of the base plate. This head, which is circular, is received into a similar shaped recess formed in 70 the base of a chair which comprises a pair of plates 8 which receive the web and base of the rail section between them and which are secured to the rail section by a plurality of bolts 9. 75

Means for swinging the rail section comprise a plurality of cam levers 10, 10^a each separately pivoted to the base plate 1 by bolts 11. In the preferred embodiment of my invention shown in the drawings four 80 such cam levers are shown, one on each side of the rail section adjacent each end. The cam levers 10, 10^a on the same side of the rail section are connected by a yoke 12, one such yoke being located on each side of the swinging rail section. The connection between the yoke and cam levers is a pin and slot as illustrated so that a reciprocating movement of the yoke will swing the cam levers 85 about their pivots. The ends of the yokes 90 are secured to locking plates 13 which slide along the web of the rail-section E at opposite sides thereof and which are suitably guided in recesses in the chair members 8 and in recesses in auxiliary chairs 14 mount- 95 ed adjacent each end of the swinging rail.

The ends of the locking plates co-operate with sockets 23^a formed between the track-rails A, B, C and D and the corresponding spreaders 3 to lock the swinging rail-section 100 against lateral displacement, in conjunction with stops 23 projecting from the track-rails at the opposite sides of their webs as will hereinafter be more fully described.

Means for reciprocating the yokes 12 are 105 provided as follows: To each yoke there is secured centrally a bent plate 15 which projects beyond the base plate and which is joined by a slotted connection to the upwardly turned ends 16 of opposite arms of 110

the four-armed or cross lever L which is pivoted on the lower reduced portion of the pivot pin 6. To the other pair of arms 17 of the lever L there are connected the operating links 18, 19. These links are connected to the opposite arms of a T-crank 20 pivoted at 21 and adapted to be oscillated by the link 22 which is actuated from the switch stand (not shown) or any power connection which 10 operates the switch, as both switch and frog are operated together.

On the sides of the rails A, B, C, and D which are outermost with relation to the movement of the section E there are provided the before-mentioned stops 23 held in position in recesses provided therefor in the plates 2. These stops serve to limit the swinging movement of the rail section E and thus insure that it will stop in proper line with either the main or switch track rail, and they assist in locking the swinging rail in its adjusted positions, by coöperation with the ends of the locking-plates 13 which occupy the sockets 23^a at the opposite sides of the rails to which the stops are fastened.

The swing-rail switch frog is prevented from rising off the pivot bolt 6 by clips 24 bolted to the base plate 1 and reaching over the chair members 8 in such position as to prevent upsetting of the chair 8 and still permit limited oscillation thereof.

A link 25, also pivoted to the T-crank 20, may be connected to mechanism for operating a derail, or signals, or both as desired.

35 Operation.

Assuming the parts to be in the position shown in Figs. 1 and 2, a pushing action on the link 22 will rock the T-crank 20 about its pivot 21 and, through the links 18, 19 will impart a similar movement to the cross lever L. Through its arms 16 with their slotted connections to their plates 15, reciprocation in opposite directions will be imparted to the yokes 12 and as a consequence to the plates 13. This reciprocation of the yokes and their attendant parts will be to the left on the near side of Fig. 2 and to the right on the far side. The first result 45 of this movement will be to withdraw opposite ends of the locking plates 13 from their respective sockets. During this initial movement the cam levers 10, 10^a of course both swing slightly about their pivots 11 but the operative faces of these levers are shaped substantially so that each end of the effective face of the cams is substantially concentric with the pivots 11. As a consequence during the initial movement of the parts, while the locking members 13 are being withdrawn, there is no tendency for the swinging section 50 to move. But after the locking bars are fully withdrawn further movement of the parts will cause the eccentric portions 55 of the cam faces of the levers 10^a to react

against the swinging section and move it from one position to the other. During this movement a corresponding swing imparted to the cam levers 10 causes these latter to clear the rail to permit this movement. As 70 the swing of the rail section is complete a further movement of the parts will cause the locking bars 13 to enter sockets provided therefor adjacent the other pair of rails. When their movement is complete 75 the cam levers 10^a will stand in the position in which the cam levers 10 are shown in the drawings and the levers 10 will be in the position in which 10^a are shown. From the foregoing it will be clear that all the cam levers swing in the same clockwise direction during each movement thereof; and that, at a given time, a diagonally opposite pair of levers are causing the rail movement and the other diagonally opposite pair of levers are receding to permit it. It will be 80 obvious that the return movement is the reverse of that just described.

At either limit of travel of the swinging section one pair of levers 10 or 10^a stand at 85 substantially right angles to the swinging section and a corresponding pair of levers stand in the position in which levers 10^a are illustrated. At this extremity of swinging the levers 10^a are engaged and held by stops 90 3^a and therefore the swinging section is securely gripped between a lever which is rigidly held against swinging and one whose pivot point and operative face are in a line substantially at right angles to the swinging member and therefore in position of equilibrium. While I have shown only a pair of cam levers 10, 10^a on each side of the swinging section it will be obvious that as 95 many of these cam levers as desired to properly brace the section may be employed.

The pivot bolt 6 and its socket taper as shown where the bolt passes through the plate 1 and this is for the purpose of causing the bolt to recenter itself if it should be 100 raised from its socket. This rising action may be caused by a locomotive coming to a stand on the swinging section and then starting with a slipping action of the drivers on the rails thus pushing the rails endwise 110 until the coinciding track rail is butted, or when a train is stopped with its brakes so firmly set that the wheels slide over the frog section.

In its operative positions the swinging rail section is retained firmly in position by coöperation of the clips 24, the wedging action of the cam levers, the entrance of the locking bars 13 into their similar shaped 115 sockets between the spacer plates 3 and the respective rails and engagement of the 120 swinging section with the stops 23. These several locking agencies coöperate insuring a firm and rigid retention of the swinging section in either position. The chairs 14 125

adjacent the ends of the swinging section serve to maintain the ends of the section at proper height to cause them to register with the ends of the rails with which they are to be brought into alignment.

5 While I have described in detail the best embodiment of my invention now known to me I do not wish to be considered as limited to the precise details shown and described 10 as it is obvious that many changes in details and arrangement may be made without departing from my invention.

Having thus described my invention what I claim and desire to secure by Letters Patent is:

15 1. In a swing-rail switch frog, a base plate, a cylindrical pivot pin projecting thereabove, a chair having a cylindrical recess in the bottom thereof, said pin being received in said recess, a rail section carried by said chair, and clips mounted on said base plate and extending over the base of said chair, whereby said chair is retained on said pivot but permitted to oscillate thereon.

20 2. In a swing-rail switch frog, a base plate, a rail section pivoted on said base plate, cam levers pivoted to said base plate on opposite sides of said rail section adjacent one end thereof, said levers having their free ends in position to engage said rail, and means for simultaneously swinging said cam levers in the same clockwise direction, one approaching said rail as the other 25 recedes therefrom.

30 3. In a swing-rail switch frog, a base plate, a rail section pivoted on said base plate, cam levers pivoted on said base plate with their free ends in position to engage said rail, a pair of said cam levers being located adjacent each end of said rail, and means for simultaneously swinging said cam levers in the same clockwise direction, one 35 diagonally opposite pair of levers effecting the rail movement and the other diagonally opposite pair of levers receding to permit it.

40 4. In a swing-rail switch frog, a base plate, a rail section pivoted on said base plate, a reciprocating yoke on each side of said rail section, a cam lever connected adjacent each end of each yoke by a pin and slot connection, said cam levers being pivoted on said base plate with their free ends in operative relation to said rail section, and means for simultaneously reciprocating 45 said yokes in opposite directions.

50 5. In a swing-rail switch frog, a rail section pivoted on said base plate, a reciprocating yoke on each side of said rail section, a cam lever connected adjacent each end of each yoke by a pin and slot connection, said cam levers being pivoted on said base plate with their free ends in operative relation to said section, locking bars rigidly connected to each end of each yoke and guided

50 on said pivoted rail section, a track structure at each end of said pivoted rail section having a pair of rails with each of which said pivoted section is adapted to be brought into line and having a socket adjacent each rail end adapted to receive a locking bar, and means for simultaneously reciprocating said yokes in opposite directions.

55 6. In a swing-rail switch frog, a base plate, a rail section pivoted on said base plate, cam levers pivoted to said base plate on opposite sides of said rail section adjacent one end thereof, said levers having their free ends in position to engage said rail and said free ends being each formed into a surface concentric with the pivot of said lever, a cam surface and a second surface concentric with said lever, and means for simultaneously swinging said cam levers in the same clockwise direction, one approaching 60 said rail as the other recedes therefrom.

65 7. In a swing-rail switch frog, a base plate, a rail section pivoted on said base plate, a reciprocating yoke on each side of said rail section and guided thereby, cam levers pivoted on said base plate with their faces in operative relation to said rail section, there being one of said cam levers connected adjacent each end of each yoke, a plate secured to each yoke and projecting beyond said base plate, a cross lever pivoted below said base plate and on the center line of the swinging rail section, two of the arms of said cross lever being connected by a pin and slot to the plates mounted on said yokes, 70 a pair of links connected to the other arms of said cross lever, and means for reciprocating said links in opposite directions.

75 8. In a swing-rail switch frog, a base plate, a rail section pivoted on said base plate, cam levers pivoted to said base plate on opposite sides of said rail section adjacent one end thereof, said levers having their free ends in position to engage said rail, means for simultaneously swinging the said 80 cam levers in the same clockwise direction, one approaching said rail as the other recedes therefrom, and a stop in position to engage each cam lever at the end of its throw in a receding direction.

85 9. In a swing-rail switch frog, a base plate, a chair pivoted on said base plate, a rail section carried by said chair, an auxiliary chair section adjacent each end of said rail section, cam levers pivoted to said base plate on opposite sides of said rail section and adjacent the ends thereof, said levers having their free ends in position to engage said rail and said free ends being each formed into a surface concentric with the pivot of said lever, a cam surface and a second surface concentric with said lever, a yoke on each side of said rail section, a locking plate connected to each end of each yoke and guided in said pivoted chair and an 90 100 105 110 115 120 125 130

auxiliary chair, one of said cam levers being connected to said yoke adjacent each end thereof by pin and slot connections, a plate carried by each yoke and projecting beyond 5 said base plate, a cross lever pivoted below said base plate on the center line of said chair, pin and slot connections between a pair of the arms of said cross lever and the

plates mounted on said yokes, a link connected to each of the other arms of said 10 cross lever, and means for reciprocating said links in opposite directions.

In testimony whereof I have hereunto affixed my signature.

CHARLES EDWARD ENNIS.
